SAFE

Filed June 11, 1928

John Hermann,
INVENTOR

BY Eugene Jacobson

ATTORNEY

UNITED STATES PATENT OFFICE

JOHN HERMANN, OF SAN FRANCISCO, CALIFORNIA

SAFE

Application filed June 11, 1928. Serial No. 284,379.

This invention relates especially though not exclusively to small built-in safes such as are used in retail stores, service stations, or the like, and in homes, and is directed particularly to certain door and lock features applicable to such safes.

Doors of one single plate or even greater thickness and of so-called drill-proof steel, having locks attached thereto by screws received in tapped holes normal to the door plate, can be attached by drilling or punching from the outside into the door plate in line with the lock-holding screws. When the screws are punched or drilled out in this way the lock will drop off and the door can be removed or opened. This method of attack is known and widely used by laymen in opening safe deposit boxes; a template giving the location of the lock-holding screws being easily obtained for this purpose.

It is an object of the present invention to provide protection against that form of attack of safes and the like known as punching or drilling out the lock-holding screws. Other objects of this invention are to teach an improved method and to provide improved means for attaching locks to safes and the like, and for securing the doors thereof.

It is an object of this invention to provide means for attaching locks of any description to doors without the use of screws, and especially without the use of screws or the like normal to the door.

Other important objects of this invention are to provide improved means respectively for preventing punching-in, prying out, or other displacement of the safe lock or door.

An important object of this invention is to teach a design which is economically and structurally practicable for small safes. Certain structural details are especially important in this connection.

Other and ancillary and variously combined objects will be suggested in the following description and in the use of the device of this invention.

Referring to the drawings:

Fig. 1 is an axial section of a closed and locked cylindrical safe embodying my invention. The plane of section of Fig. 1 is

indicated by lines 1-1 in Figs. 3 and 5. Fig. 2 is an axial section of the upper portion of the safe with its door removed. The plane of section of Fig. 2 is also represented by the line 1-1 in Fig. 5. Fig. 3 is an end elevation of the safe door turned through ninety degrees from the locking position shown in Fig. 1. The door in Fig. 3 is shown above, and in angular position to be inserted into, the safe of Fig. 2. Fig. 4 is a bottom plan view of the safe door removed from the safe. Fig. 5 is a fragmentary plan view of the safe with its door removed.

A metal safe body is formed by a heavy steel casting 1, preferably of cylindrical deep cup shape with a door-way opening at its rim. An outer circular door plate 2 is provided to close the door-way opening; the door-way being rabbeted or counterbored to a diameter and depth to flushly receive the door plate. A substantial shoulder 1a is left in the safe body below the counterbore to resist battering in the door plate.

The door plate 2 is held in the safe body by a cylindrical bayonet-type tongue-and-groove joint so that the door may be inserted or removed only when rotated to a particular angular position relative to the safe body. This door joint will subsequently be described more in detail.

A lock 3 is provided for locking the door against rotation in the safe body. The lock employed is preferably a conventional safe-deposit-type key-operated lock 3 having a sliding locking bolt 3a which may be moved by means of keys 4 and 5 into a radial slot or keeper at 1b in the shoulder 1a of the safe body.

A tongue and groove joint is provided for securing the lock 3 to the safe door. A parallel spaced pair of massive integral flanges 2a and 2a' depend from the inside face of the door plate 2; the door plate and its flanges being one integral solid steel casting. The lock is held against the door plate between the flanges thereof by a heavy plane plate or backing member 6, which is in turn held directly by the massive flanges 2a and 2a'. The flanges are provided with opposed longitudinal slots parallel to the plate 2 at the level

of the back face of the lock 3. The slots form ways which receive and hold the longitudinal or side edges of the backing plate 6 (see Fig. 3).

The plate 6 is long enough to prevent its longitudinal displacement when in the safe (see Fig. 1), and is slightly tapered so that it may be jammed into its joint to prevent it from dropping out when the door is removed from the safe and also to provide a tighter joint than would otherwise be practicable.

The backing plate 6, supported behind the lock by a tongue and groove joint parallel to and partly integral with the door plate 2, practically insures against battering in of the lock. The lock abuts against the door plate, so it cannot be pried out. Displacement of the lock in directions parallel to the door plate is prevented by the flanges 2a and 2a' and by the wall of the safe body; the lock being substantially as wide as the space between the flanges, and but slightly shorter than the internal diameter of the safe.

It will be observed that the lock 3 is secured to the door 2 without the necessary use of screws, rivets, pins, or like fasteners, which could be drilled out.

The main joint which holds the door in the safe will next be described. The end edges of the plate 6 are employed directly as the tongues of the main tongue-and-groove bayonet joint which holds the door in the safe; the plate 6 being appreciably longer than the minimum diameter of the safe. An annular groove of generous depth is left in the safe body below the shoulder 1a. The groove is of a diameter to freely receive the ends of the plate 6. Thus the shoulder 1a not only prevents the door from being battered in, but also abuts against the end edges of plate 6 to prevent the door from being pried out. The shoulder 1a is notched at 1c and similarly at the diametrically opposed position 1c', to permit insertion and removal of the door after same has been rotated through ninety degrees (i. e. to the position of Fig. 3) from its locking position (shown by Fig. 1). A handle 7 of light construction is provided to facilitate handling of the door.

For residence use, the safe may be built into the wall, but in general it is preferable to embed the safe as shown, in the concrete or other floor 8, with its door-way at the floor level. A plurality of radially projecting integral anchor lugs or flanges 1d extend from the base of the safe body and are adapted to secure it in its concrete or other suitable foundation.

A radial extension 1e of the upper portion of the safe body has a curved coin conduit formed therein at 1f leading from the surface to the interior of the safe.

A steel reinforcing band 9 is welded to the periphery of the safe at its rim.

While the aforescribed device of my in-

vention without the use of screws, rivets, pins, or like vulnerable fasteners, is adapted to resist displacements of the lock which would permit the safe door to be opened, yet it is recognized that such vulnerable fasteners might be superimposed thereupon for auxiliary or secondary holding power. It is therefore proper to consider devices within the purview of my invention so long as they are "essentially" and "effectively" free or independent of screws and the like—especially screws normal (i. e. perpendicular) to the safe door. The terms "essentially" and "effectively" are employed to distinguish an essential or primary use of screws or the like, from a mere superimposition or auxiliary use thereof upon an otherwise complete joint.

I have described one embodiment of my invention in detail, but it is emphasized that this embodiment is illustrative and not inclusive of all the forms my invention may assume. Certain of the objects, or certain portions or combinations of the objects of my invention may be attained with the use of less than all its advantageous features or with modifications within its purview. It is petitioned that my invention be limited only by the claims constituting its final determination.

I claim:

1. In combination, a safe body having a circular door-way, a circular safe door therefor, a pair of massive integral flanges on the inside face of said door, a lock abutting against the inside face of said door between said flanges; said lock being substantially as long as the diameter of said door-way and substantially as wide as the distance between said flanges; and a long backing plate secured behind said lock by said flanges; said flanges being grooved longitudinally and substantially parallel to said door to receive and hold the side edges of said backing plate, and said doorway being slotted and grooved to form a bayonet-type joint with the end edges of said backing plate.

2. In combination, a safe body, a safe door, a pair of integral flanges on the inside face of said door, a lock abutting against the inside face of said door between said flanges, a backing member behind said lock, a tongue and groove joint generally parallel to said door for securing said backing member to said flanges, and a second tongue and groove joint including said backing member and formed at a plurality of sides thereof for securing said door in said safe body.

3. In combination; a pair of elements one of which constitutes a door and the other of which forms a door-way therefor; a lock mounted on one of said elements and having a bolt adapted to engage the other of said elements; a backing member behind said lock; a tongue and groove joint between said backing member and an integral part of one of

said elements; and a second tongue and groove joint also including said backing member and formed at a plurality of sides thereof for holding the door element in the door-way element.

4. In combination; a safe body having a circular door-way, a circular safe door therefor, a pair of massive integral flanges on the inside face of said door, a lock abutting against the inside face of said door between said flanges, and a long backing plate secured behind said lock by said flanges; said flanges being grooved longitudinally and substantially parallel to said door to receive and hold the said edges of said backing plate, and said doorway being slotted and grooved to form a bayonet-type joint with the end edges of said backing plate.

5. In combination, a safe body having a door-receiving cavity, a safe door therefor, and a lock mounted on said door; said lock being substantially as long as the portion of said cavity into which it projects, whereby to prevent its lengthwise displacement; and backing means behind said lock to resist displacement thereof by punching in the lock.

6. In combination, a safe body having a door-receiving cavity, a safe door therefor, a lock mounted on said door, and means integral with said door for preventing sidewise displacement of said lock; said lock being substantially as long as the portion of said cavity into which it projects, whereby to prevent its lengthwise displacement.

7. A safe assembly comprising a safe body element having a circular doorway, a circular safe door element, a bayonet-type tongue and groove joint engageable by rotation of said door element in its own plane for securing the door element in the doorway, a safe lock having a locking bolt for locking said door element against rotation; one of the aforesaid members having a keeper to receive said locking bolt and the other of the aforesaid members having integral flanges depending inward therefrom and spaced apart to receive said lock; and a backing member included in said bayonet-type joint and in turn joined to said flanges and secured thereby behind said lock.

8. A safe assembly comprising a safe body member having a circular doorway, a circular safe door member, a bayonet-type tongue and groove joint engageable by rotation of said door member in its own plane for securing the door member in the doorway, a safe lock for locking said door member against rotation in said doorway, a backing member behind said lock to prevent punching in thereof, and fastening means penetrating no nearer the outer surface of said assembly than three quarters of the average wall thickness thereof for fixedly securing said backing member to said assembly;

said backing member being included in said bayonet-type joint.

9. A safe assembly comprising a safe body having a circular doorway, a circular safe door constituted of an inner door plate and an outer door plate, fastening means penetrating no nearer the outer surface of said outer door plate than three quarters of the average thickness thereof for securing said door plates together, a bayonet-type tongue and groove joint including said inner plate and engageable by rotation of said door in its own plane for securing the door in the doorway, and a safe lock nested between said door plates for locking said door against rotation.

10. A safe assembly comprising a safe body member having a circular doorway, a circular safe door member, a bayonet-type tongue and groove joint engageable by rotation of said door member in its own plane for securing the door member in the doorway, a safe lock for locking said door member against rotation, a backing member included in said bayonet-type joint and positioned behind said lock to prevent punching in thereof, and a joint including an integral portion of one of said members for securing said backing member to said assembly; the last recited joint being of elongated oblong shape generally parallel to the outside surface of said assembly nearest thereto.

11. A safe assembly comprising a safe body having a circular doorway, a safe door constituted of an inner door plate and a circular outer door plate, a bayonet-type tongue and groove joint including said inner plate and engageable by rotation of the door in its own plane for securing said door in the doorway, a safe lock nested between said door plates for locking said door against rotation, and a joint including an integral portion of said outer door plate for securing said door plates together; the last recited joint being of elongated oblong shape generally parallel to the outside surface of said outer door plate.

12. A safe assembly comprising a safe body having a circular doorway, a safe door constituted of an inner door plate and a circular outer door plate, a bayonet-type tongue and groove joint including said inner plate and engageable by rotation of the door in its own plane for securing said door in the doorway, a safe lock nested between said door plates for locking said door against rotation, and a joint including an integral portion of said outer door plate for securing said door plates together; the last recited joint having a greater area of extent generally parallel to the outer surface of said outer door plate than a screw joint of equal holding power.

13. A safe assembly comprising a safe body having a circular doorway, a safe door constituted of an inner door plate and a circular outer door plate, a bayonet-type tongue

and groove joint including said inner plate and engageable by rotation of the door in its own plane for securing said door in the doorway, a safe lock nested between said door
5 plates for locking said door against rotation, and a joint including an integral portion of said outer door plate for securing said door plates together; the last recited joint having a greater linear extent generally parallel to
10 the outer surface of said outer door plate than a screw joint of equal holding power.
